[57] CLAIM

The ornamental design for a flexible net for a dishwasher rack, as shown and described.

DESCRIPTION

FIG. 1 is a top, front and right side perspective view of a flexible net for a dishwasher rack showing my new design; FIG. 2 is a top plan view thereof;

FIG. 3 is a bottom plan view thereof;

FIG. 4 is a front elevational view thereof, with the rear constituting a mirror-image of the front; and,

FIG. 5 is a right side elevational view thereof, with the left side constituting a mirror-image of the right side.
